(57) **CLAIM**

The ornamental design for the shovel handle, as shown.

DESCRIPTION

FIG. 1 is a perspective view of a shovel handle.

FIG. 2 is a bottom view of the shovel handle.

FIG. 3 is a front view of the shovel handle.

FIG. 4 is a top view of the shovel handle; and,
FIG. 5 is a side view of the shovel handle.

The broken line showing of a shovel blade is for illustrative purposes only and forms no part of the claimed design.
